UNITED STATES PATENT OFFICE

171,278

PENCIL SHARPENER

Dillon Charles Furey, Melbourne,
Victoria, Australia

Application March 13, 1953, Serial No. 24,021

Term of patent 3½ years

(Cl. D74—21)

To all whom it may concern:

Be it known that I, Dillon Charles Furey, a subject of the Queen of Great Britain, residing at Melbourne, in the State of Victoria, Commonwealth of Australia, have invented a new, original, and ornamental Design for Pencil Sharpeners, of which the following is a specification, reference being had to the accompanying drawing, forming a part hereof.

Figure 1 is a perspective view of a pencil sharpener, showing my new design;

Figure 2 is a top plan view of the pencil sharpener shown in Figure 1;

Figure 3 is a bottom plan view thereof;

Figure 4 is a rear elevational view; and

Figure 5 is a side elevational view thereof.

I claim:

The ornamental design for a pencil sharpener, as shown.

DILLON CHARLES FUREY.
